UNITED STATES PATENT OFFICE.

HARRY ANGEL, OF LOS ANGELES, CALIFORNIA.

COLUMN PARLOR-FLOOR LAMP.

Application filed January 4, 1926. Serial No. 79,133.

This invention relates to column parlor floor lamps.

The general object of the invention is to provide a parlor floor lamp wherein means is provided for illuminating the lamp throughout the entire column.

Another object of the invention is to provide a column lamp wherein an illuminated pedestal is surmounted by a lamp and wherein in the lamp and the pedestal may be selectively lighted at will.

A further object of the invention is to provide a specific mounting for transparent panels for floor lamps.

Other objects of the invention will be apparent from the following description taken in connection with the accompanying drawings, wherein:

Fig. 1 is a perspective view of a column floor lamp embodying the features of my invention;

Fig. 2 is a central sectional view through a lamp;

Fig. 3 is a section on line 3—3, Fig. 2;

Fig. 4 is a section on line 4—4, Fig. 2;

Fig. 5 is a perspective view of a spacing block;

Fig. 6 is a wiring diagram, and

Fig. 7 is a sectional view showing a modified form of my invention.

Referring to the drawing by reference characters, I have indicated my lamp generally at 10. This lamp comprises a plurality of base or foot members 11 which have corner column members 12 secured thereto.

Spaced along the column members 12 I arrange partition members 14 which are preferably opaque. These partition members 14 may be of any desired configuration depending upon the shape of lamp desired. In the preferred embodiment of my invention here shown I show the partition members 14 as rectangular. Each partition member 14 is shown as provided with a plurality of apertures 15. These apertures serve to provide ventilation to prevent the heat generated by the lamps from destroying the lamp. The apertures 15 also provide holes through which the electric wires used with the lamp may be passed.

The corner column members 12 are shown as rabbeted at 16 in Figs. 3 and 4. In the slots thus provided I slide transparent or translucent panels 17 which may be ornamental or plain as desired. These panels 17

are freely movable in the slots and are preferably of such a length that they will extend substantially from one partition member 14 to the other as clearly shown in Fig. 2.

Between each of the panel members 17 I insert spacing blocks 18 which are shown in detail in Fig. 5. These spacing blocks each comprise a body portion 19 having a front flange 20 thereon. This front flange 20 is continuous throughout the full length of the spacing block. The body of the spacing block is also provided with a rear flange 21 which is cut away as at 22 to provide an aperture for ventilation.

The spacing blocks 18 are adapted to have their ends in tight engagement with the opposed face of the corner members 12 so that they will be held by this engagement and also by the engagement of the panel 17 in the upper and lower slots of the spacing block.

On the upper surface of each of the partition members 14 I also arrange a lamp socket 30 and on the lowermost partition I arrange a lamp 31 upon the under surface.

I will here state that the number of partitions and number of transparent panels provided may be changed to suit conditions. I now prefer to make either four or five compartments although this number may be changed to suit the particular wishes of the manufacturer.

The lamp sockets 30 and 31 have one terminal thereof connected to a lead 32 which is in communication with a suitable source of electricity. The other terminal of each lamp socket is in circuit with another lead 33 which is connected to one member 34 of a switch. The other member 35 of the switch is connected to a lead 36 which is also in communication with the source of electricity. A circuit closure 37 is adapted to bridge the members 34 and 35 to close the circuit and illuminate the lamps 30 and 31. The member 35 of the circuit closure 37 may be of any desired construction and the arrangement shown is simply for the purpose of illustration.

Upon the upper end of the column I provide a closure member 40 (see Fig. 2) which has a post 41 thereon which serves to support a fixture 42 having lamp sockets and lamps 43 and 44 thereon. The lamp socket 43 has one terminal 45 thereof secured to a member 46 of a circuit closure 47. The cir-

cuit closure 47 is connected to the lead 32. The other terminal 48 of the lamp 43 is connected by means of a lead 49 with the lead 36 previously mentioned. It will thus be apparent that by operating the member 47 the lamp 43 will be lighted.

The lamp 44 has a terminal 50 thereon connected to a lead 51 which is in circuit with the lead 32 previously mentioned. The other terminal 52 of the lamp 44 is in circuit with a member 53 of a circuit closure 54. The circuit closure 54 communicates through a lead 55 with the lead 36. It will thus be apparent that when the circuit closure member 54 is operated the lamp 44 will be illuminated. It will thus be apparent that from the foregoing description that either of the lamps 43 or 44 may be illuminated independently of the lamps 30 and 31 so that selectivity of lighting arrangement is provided.

In Fig. 7 I show a modified form of my invention wherein corner members 60 support panels 61. The construction of this modification is similar to that of the preferred embodiment except that I show here a six sided lamp. If desired I may make a lamp having any number of sides.

From the foregoing description it will be apparent that I have provided an improved column parlor floor lamp which is durable and which is not likely to get out of order.

Having thus described my invention, I claim:

1. A parlor floor lamp comprising a vertical pedestal having a base thereon, said pedestal comprising a plurality of corner members, spaced partition members arranged

along said pedestal, said partition members being opaque, a plurality of transparent panels mounted on said corner members, a lamp disposed on each of said partition members, a lamp extending above the top of said pedestal, means to supply electric current to said lamps on said partitions and other means to supply current to said top lamp.

2. A column lamp comprising a base, a plurality of members projecting upwardly from said base, said members being L-shaped in cross section and having grooves in certain faces thereof, transparent panels mounted in said grooves, spacing blocks between said panels, said spacing blocks comprising a body having a front and back flange, said front flange being continuous across the entire body and the back flange being removed in the middle of said body to provide ventilation, lamps mounted adjacent to said transparent panels and means to supply current to said lamps.

3. A parlor floor lamp comprising an elongated pedestal having a base thereon, said pedestal comprising a plurality of vertically arranged spaced corner members, transverse spaced partition members arranged along said corner members to provide compartments, a plurality of transparent panels, said panels being slidably mounted directly on said corner members and being readily removable, a lamp disposed in each of said compartments, and means to supply electric current to said lamps.

In testimony whereof, I hereunto affix my signature.

HARRY ANGEL.
